UNITED STATES PATENT OFFICE.

JOSEPH MAZER, OF McALESTER, OKLAHOMA.

WINDING-INDICATOR.

1,108,509.

Specification of Letters Patent. Patented Aug. 25, 1914.

Application filed April 21, 1911. Serial No. 622,585.

To all whom it may concern:

Be it known that I, JOSEPH MAZER, a citizen of the United States, and resident of McAlester, in the county of Pittsburg and State of Oklahoma, have invented a new and useful Improvement in Winding-Indicators; and I do hereby declare the following to be a full, clear, and exact description thereof.

10 My invention relates to a winding indicator for watches, clocks, phonographs and other devices to which it may be applicable, whereby it is possible from a dial to tell not only when the spring is fully wound or 15 when it is run down, but also the extent to which it is wound at any particular moment and the time when it will require rewinding.

The object of my invention is to provide mechanism of this character in which 20 bridges or plates for holding the parts together are dispensed with, thereby saving the room which such plates would require and enabling me to place the mechanism in a narrow space to reduce the thickness of 25 the watch where used in connection with same.

A further object of my invention is to provide a winding indicator construction which will not in any way interfere with the 30 mechanism of a pendent set watch or even of the lever set watch.

Other objects of my invention will appear in the further disclosure of the invention.

In the drawings, Figure 1 is a face view 35 of a watch showing my winding indicator applied thereto; Fig. 2 is a large diagrammatic view showing the gear-wheel connections; Fig. 3 is a section on the line 3-3 Fig. 2; Fig. 4 is a section on the line 4-4 Fig. 2; Fig. 5 is a detail of the planetary gearing; Fig. 6 is a detail of the plate for supporting the gear to the indicator hand, and Fig. 7 is a modified form of my invention.

45 Referring to the drawings I have illustrated my invention in connection with a watch A which is a stem winding watch of the pendent set type, but for the purposes of description it will not be necessary to refer to the movement of the watch, which 50 may be of any suitable type. The body of the watch comprises the upper and lower plates B and B'. Located in the recess C in the plate B' is the main-spring barrel o 55 provided with arbor o⁶ to which is attached the spring o'. Secured to the arbor o⁶ is

the ratchet-wheel k which meshes with the gear wheel J on the shaft J'. The shaft J' has the bearing in the plate B' and secured to the upper end of said shaft is the pinion i which meshes with the gear-wheel h secured by the screw h' to the plate B. The gear-wheel h meshes with the gear-wheel g. The gear-wheel g is mounted loosely on the pinion o² said pinion acting as a bearing for 60 said gear wheel g. This pinion o² is secured by the pin o³ to the barrel o. The main-spring barrel head has a thickened portion o⁴ which bears against the gear-wheel g and acts as a cap to hold said gear-wheel in place. 65

The pinion o² is provided with the teeth o⁵ which mesh with the teeth f of the planet gear F. The planet gear F is secured by the screw f' to the wheel g and said planet gear has the teeth e which mesh with the teeth d of the double pinion D. This pinion D is mounted loosely on the pin d' which is stepped in the frame B, B'. The teeth c of the double pinion D mesh with the gear-wheel b which is secured by the screw b' to the plate B. The gear-wheel b meshes with the gear-wheel a which carries the indicator-hand a². The gear-wheel a is carried by the extension r' of the plate r. This plate r is located to one side of the winding 75 indicator dial and is held by screws r² to plate B and the extension r' extends over into position to receive the gear-wheel a which registers with the indication dial of the winding indicator. The extension r' has 80 the flange r³ which is cut away as at r⁴ to expose the teeth of the gear-wheel a. The extension r' has the stud r⁵ upon which the gear-wheel a is mounted. The indicator-hand a² is carried directly by the gear-wheel a as indicated in Fig. 4. 85

I will now describe the connections from the winding-stem to the main-spring barrel. The winding-stem s has the bevel pinion s' which meshes with the crown-wheel l. The 90 crown-wheel l meshes with the ratchet-wheel k, and the spring o' being attached to said ratchet through the arbor o⁶, when the winding mechanism is operated the spring will be wound up in the barrel o through the connections just described.

When the watch is unwinding the spring o' will turn the barrel o, the ratchet k being held against turning and this rotation of the barrel o will impart a like rotary movement 105 to the pinion o² secured to said barrel. The pinion o² engages the teeth f of the planet-

gear F and as the gear-wheel g is indirectly held by the ratchet, no rotary movement is imparted to said gear g. The planet-gear F has its teeth e meshing with the teeth d of the double pinion D loosely mounted upon d'. The teeth o of the double pinion D mesh with the teeth of the gear-wheel b and b meshes with a, whereby the indicator hand is operated.

10 When it is desired to wind up the watch and bring the indicator hand back to zero the operation is as follows:

The winding of the stem s turns the crown-wheel l and as said crown-wheel meshes with the ratchet h connected to arbor o⁶, the spring o' is wound up by the rotation of said ratchet-wheel. At the same time the ratchet-wheel h meshes with the gear-wheel J and in this way rotary motion is imparted to pinion i. From the pinion i power is transmitted to the gear-wheel h which in turn imparts rotary movement to the gear-wheel g. The gear-wheel g being loosely mounted on the pinion o², the planet-gear F will be carried around by the gear-wheel g and the reverse movement will be imparted to the double pinion D which will operate through the gear-wheel b to reverse the gear-wheel a and bring the indicator hand back to zero. 30 The planet gear travels around the pinion o² which remains stationary.

One of the chief advantages of the above arrangement is that it requires but one recess E on that side in the plate B in which recess is located the gear-wheel g and all the other wheels necessary for the reversing motion. Furthermore the gear-wheel g has a recessed portion g' which forms a space to receive the planet-gear, and the lower 35 toothed face of double pinion D. The face of said gear-wheel is close up to the inner face of the recess E, so as to form a practically dust proof arrangement, as the face of the gear-wheel forms the dust-cap on one side and the inner face of the recess E the other cap.

40 By having the thickened portion o⁴ on the main-spring barrel, it is unnecessary to have any retaining plates, thereby saving the room which such plates would require and making it possible to put the mechanism in a narrower space. Furthermore, but four planes are required for the entire mechanism, while ordinarily not less than six or seven 45 planes were required to provide for the mechanism, thereby greatly increasing the amount of space required.

50 By the employment of the support r and extension plate r' I am enabled to locate the winding indicator dial in line with the second hand of the watch, and that too without interfering in any way with the mechanism of the pendent-set watch. Heretofore it has been practically impossible to mount a winding 55 indicator on the pendent set watch due

to the fact that the pendent set mechanism being generally between the plates interfered with any other wheels that might be necessary to locate there. Or even when they were on the under side of the dial, still the springs and levers would interfere, making it impossible to go through. With my arrangement coming through immediately under the barrel where it would be impossible to have pendent set springs of any character in the usual construction, I completely avoid that objection and apply my winding indicator mechanism just as readily on the pendent set as on the lever set watch, and even in the lever set watch it has been frequently found necessary to make changes in the ordinary construction of the watch to permit the placing of the winding indicator mechanism.

55 In Fig. 7 I have illustrated a modified form of my invention in which the extension r is dispensed with, and the plate y bridges the space for the pendent set mechanism, said plate being secured by the screws x. The gear-wheel a is supported by the plate y, 80 said plate having the stud y' to receive said gear-wheel.

85 What I claim is:

1. In a watch or the like, the combination of the main-spring barrel, of winding mechanism including a ratchet wheel, a pinion carried by said barrel, a recessed gear-wheel loosely mounted on said pinion, connections between said gear wheel and said ratchet wheel, reversing mechanism carried by said gear-wheel and engaged by said pinion, said reversing mechanism being contained within the space formed by said recessed wheel and the inner face of the watch-plate. 95

100 2. In a watch or the like, the combination of the main-spring barrel, of winding mechanism including a ratchet wheel, a pinion on said main-spring barrel, a recessed gear-wheel through which said pinion extends and forming a bearing for same, connections between said gear wheel and said ratchet wheel, reversing mechanism carried by said recessed-gear and engaged by said pinion, said reversing mechanism being contained within the space formed by said recessed-gear and the inner face of the watch-plate. 115

110 3. In a watch or the like, the combination with the main-spring barrel, of winding mechanism including a ratchet wheel, a pinion on said barrel, a recessed gear-wheel located in a recess formed in the watch-plate, said pinion passing up through said gear-wheel and forming a bearing for same, connections between said gear wheel and said ratchet wheel, reversing mechanism carried by said dished gear-wheel in the space between said recessed gear-wheel and the inner face of the recess, said reversing mechanism being engaged by said pinion. 120

125 4. In a watch or the like, the combination

with the main-spring barrel, of winding mechanism including a ratchet wheel, a pinion carried by said barrel, a recessed gear-wheel, said pinion extending up through said gear-wheel and forming a bearing therefor, means for spacing said gear-wheel from said spring-barrel, connections between said gear-wheel and ratchet wheel, reversing mechanism carried by said gear-wheel in the space between the gear-wheel and the inner face of a recess formed in the watch-plate, said reversing mechanism being engaged by said pinion.

5. In a watch or the like, the combination of the main-spring barrel, of winding mechanism, a pinion carried by said barrel, a gear-wheel, said pinion extending up through an opening in said gear-wheel and forming a bearing on which said gear-wheel is loosely mounted, a planet-gear carried by said gear-wheel engaged by said pinion, a double pinion in line with said first named pinion and engaged by said planet-gear, a winding indicator-hand, and connections between said indicator-hand and said double pinion.

6. In a watch or the like, the combination of the main-spring barrel, of winding mechanism, including a ratchet-wheel attached to

the spring of said barrel, a gear-wheel, connections between said gear-wheel and said ratchet-wheel, a pinion on said main-spring barrel extending up through said gear-wheel and forming a bearing on which said gear-wheel is loosely mounted, a planet-gear carried by said gear-wheel and engaged by said pinion, a double pinion in line with said first pinion engaged by said planet-gear, and connections between said double pinion and said winding indicator hand.

7. In a watch or the like, the combination of the main-spring barrel, of winding mechanism, a winding indicator hand, a pinion carried by said barrel, a gear-wheel through which said pinion extends to form a bearing for said gear-wheel, an enlarged portion on said barrel which bears against said gear-wheel, connections between said pinion and said indicator hand, and connections between said gear-wheel and said hand in winding to bring said hand back to zero.

In testimony whereof, I the said JOSEPH MAZER have hereunto set my hand.

JOSEPH MAZER.
